POWDER BOX COMPACT

Ada C. Marcellus, New York, N. Y.

Application February 9, 1949, Serial No. 75,329

5 Claims. (Cl. 222—205)

1

This invention relates to new and useful improvements in a device for feeding pulverized or granulated material and proposes certain improvements in the construction shown in my earlier application Serial No. 763,367, filed July 24, 1947, now matured into Patent No. 2,568,814, dated September 25, 1951.

More specifically, the present invention proposes the construction of an improved device for feeding pulverized or granulated material and, more specifically, relates to a device for feeding small quantities of face powder upward within its containing box so that it may be conveniently picked up with a conventional powder puff and applied to the face in the usual manner.

Another object of the present invention proposes characterizing the device by a flat disc which is adapted to be rotated on the top surface of the pulverized or granulated material; such as face powder, and which is provided with depending scoops arranged in a manner to feed small quantities of the pulverized or granulated material onto the top face of the disc as the disc is given a partial rotation.

Still another object of the present invention proposes forming the center of the disc with a formation for throwing the pulverized or granulated material laterally to the sides as the disc is rotated for preventing the material from caking beneath the center of the disc and restrain downward movement of the disc.

The invention further proposes providing the top of the disc with a handle by which a grip may be conveniently had on the disc for rotating the same.

A further object of the present invention proposes pivotally mounting the handle on the top face of the disc in a manner so that the handle may be pivoted to an out of the way position extended parallel to the top of the disc.

A still further object of the present invention proposes providing the edge of the disc with a depending knife for severing the top protective cover of paper usually applied to the inside of powder boxes or any box or container having pulverized or granulated material.

Another object of the present invention proposes forming the disc of a thin sheet of metallic or plastic material and to provide it about its periphery with a reinforcing means in a manner to stiffen the disc and lessen its chances of becoming misshapen in use.

The present invention also proposes forming the sides or one side of the scoop with small notches extended into the material of the scoop from the

open ends thereof in a manner to impart some resiliency to the scoop to prevent the pulverized or granulated material from becoming stuck in the scoop and to permit some entrance of the pulverized or granulated material into the scoop from the side or sides thereof.

It is a further object of this invention to construct a device for feeding pulverized or granulated material which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

20 Fig. 1 is a perspective view of the device for feeding pulverized material constructed in accordance with the present invention.

Fig. 2 is an enlarged partial side elevational view of Fig. 1.

25 Fig. 3 is an enlarged partial sectional view taken on the line 3—3 of Fig. 1.

Fig. 4 is a partial transverse sectional view taken on the line 4—4 of Fig. 3.

30 Fig. 5 is an enlarged partial transverse sectional view taken on the line 5—5 of Fig. 1.

Fig. 6 is a vertical sectional view of a conventional powder box having its top cover removed and with the device for feeding pulverized or granulated material in accordance with the present invention, applied thereto.

35 Fig. 7 is a plan view of the device for feeding pulverized or granulated material constructed in accordance with a modification of the present invention.

40 Fig. 8 is a plan view similar to Fig. 7, but illustrating a further modification of the present invention.

Fig. 9 is a partial side elevational view of Fig. 8.

45 Fig. 10 is an enlarged partial transverse sectional view taken on the line 10—10 of Fig. 8.

Fig. 11 is a perspective view of one of the scoops of the form of the invention shown in Figs. 8 to 10, looking at the side of the scoop facing toward the center of the device.

The device for feeding pulverized or granulated material, according to the form of the invention shown in Figs. 1 to 6, includes a flat disc 20. The disc 20 is preferably circular in plan and is formed of a thin sheet of metallic or plastic material and

is reinforced by a downwardly depressed circular rib 21 formed in the disc adjacent the periphery thereof. The rib 21 stiffens the disc 20 and prevents it from becoming misshapen in use.

While the disc 20 is illustrated on the drawing as being reinforced by a downwardly pressed rib 21, this is by way of illustration only, as the rib could be upwardly pressed or the disc could be reinforced by bending the periphery of the disc into a depending flange, by forming the disc with a roller edge or by bending the periphery of the disc under.

A handle 22 is provided which forms a convenient grip by which the disc 20 can be rotated. The handle is formed of an elongated strip of metallic or plastic material and has its ends pivotally secured to lugs 23 by pivot pins 24. The lugs 23 are stamped from the material of the disc 20, within the circular rib 21, and are bent to extend vertically therefrom.

The center of the disc 20 is formed with a downwardly pressed formation 25 which is to engage the pulverized or granulated material beneath the center of the disc 20 and continuously feed the material outward as the disc is rotated. This action will prevent the material from caking beneath the center of the disc 20 where it will interfere with the downward movement of the disc with relation to the material. On the drawing, the formation 25 is shown in the shape of a four-pointed star, but this is by way of illustration only, as the formation may take any shape which will effectively feed the material outward from beneath the center of the disc.

A plurality of scoops 26 are pressed from the material of the disc 20 and those scoops have their open ends faced in the direction in which the disc 20 is to be rotated so as to feed the pulverized or granulated material upward onto the top face of the disc 20. The direction of rotation of the disc 20 is illustrated by the arrow A in Fig. 1. From Fig. 1 it will be noted that the scoops 26 are arranged in concentric circles with the scoops of each outermost circle larger than the scoops 26 of each adjacent innermost circle. As the scoops 26 of the outermost circles must operate over a greater surface of the pulverized or granulated material, forming those scoops of a larger size will serve to feed the material of the top surface evenly upward through the disc 20 so as to keep the top surface of the pulverized or granulated material flat at all times with an even distribution.

As shown in Figs. 2 to 5, the side walls of the scoops 26 are formed with small triangular notches 26^a extended inwards from the open ends of the scoops 26. The notches 26^a render the scoops 26 somewhat resilient preventing the pulverized or granulated material from becoming jammed in the scoops and also permitting the pulverized or granulated material to enter the scoops 26 from the sides thereof through the notches 26^a. The notches 26^a further provide for ventilation of the top surface of the pulverized or granulated material by providing openings for the circulation of greater amounts of air between the bottom face of the disc 20 and the top surface of the granulated material.

One side of the disc 20 is formed at the peripheral edge thereof with a depended knife member 27, see Figs. 1 and 6, for the purpose of severing the sheet of paper which usually covers the pulverized powder box or the top of

the pulverizer or granulated material in a similar container.

After the knife member 27 has been used for its intended purpose it may be bent under to extend parallel to the bottom face of the disc 20. In this position, the knife member 27 will not interfere with the operation of the scoops 26 in lifting the pulverized or granulated material from the very bottom of the box or container.

The operation of this first form of the invention is as follows:

While the device of the present invention has general application for feeding pulverized or granulated material it is designed chiefly for feeding pulverized face powder upward within a powder box, and in Fig. 6 the device is shown applied to such a powder box 28. Normally, such boxes are covered by a cover, not shown on the drawing. The box 28 contains pulverized face powder 29 and is enclosed within the box 28, when purchased, by a piece of paper 30 fixedly secured in position slightly below the top of the box forming a chamber 31, above the piece of paper 30, in which a powder puff (not shown) is usually placed.

In Fig. 6, the device of the present invention is shown rested on the top face of the piece of paper 30 with its knife member 27 piercing the piece of paper 30 at one side thereof. The handle 22 is extended vertically and may be used to give the device one complete revolution so that the knife member 27 will completely sever the piece of paper 30 from the interior of the box. The device is then lifted out of the box and the piece of paper 30 removed and discarded.

The knife member 27 having served its purpose, is now bent out of the way beneath the disc 20 to extend parallel to the bottom face of the disc. Then, the device is returned to the box to rest on the top surface of the pulverized face powder 29.

With the handle 22 extended vertically, the device is given a partial turn in the direction of the arrow A in Fig. 1 to cause some of the face powder 29 to be fed upward through the scoops 26 onto the top face of the disc 20. When the desired quantity of the face powder has been fed upward, the handle 22 is pivoted downward, on either side of the lugs 23 to lie flat against the top face of the disc 20. A powder puff may then be used in the conventional manner to pick up some of the pulverized powder from the top face of the disc 20.

In the modification of the invention shown in Fig. 7, the construction of the device for feeding the pulverized or granulated material is similar to that previously described, except that the scoops 26' are formed in the disc 20' so that they extend at an angle to the direction of rotation of the disc 20', which is illustrated in Fig. 7 by the arrow B.

On the drawing, Fig. 7 illustrates the scoops 26' as being extended at an angle of approximately 45 degrees to the direction of rotation of the disc 20', but this angle may be varied in accordance with the particular requirements of the pulverized or granulated material to be fed upward through the scoops of the device.

In other respects, this form of the invention is similar to the previous form and like reference numerals identify like parts in each of the several views.

The further modification of the invention shown in Figs. 8 to 10 includes a flat disc 40

formed of a thin sheet of sheet metal which has its edge portion reinforced by a downwardly bent narrow flange 41.

The top of the disc 40 is provided with a handle 42 by which the disc 40 can be rotated. The handle 42 is formed of a length of wire bent into an inverted U-shape and which has its ends bent into laterally inwardly extending trunnions 43. The trunnions 43 are rotatively received in complementary bosses 44 stamped from the material of the disc 40. The engagement of the trunnions 43 with the bosses 44 permits the handle 42 to be pivoted between a position extended vertically upwards from the top face of the disc 40 and a position flat against the top face of the disc 40 on either side of the bosses 44.

The center of the disc 40 is formed with a four-pointed star formation 45, see Fig. 8, for the purpose of feeding the pulverized or granulated material outwards so as to prevent it from caking beneath the center of the disc 40.

A plurality of scoops 46 are stamped from the material of the disc 40 and are arranged in spiral lines extending from the periphery of the disc 40 toward the center thereof, with the scoops being progressively smaller toward the center of the disc. The open sides of the scoops 46 are extended substantially in the direction of rotation of the disc 40 which is illustrated in Fig. 8 by the arrow C.

The sides of the scoops 46 faced in the direction of rotation of the disc 40 are formed with notches 46^a, see Fig. 11, extended inward from the open sides of the scoops. The notches 46^a render the scoops somewhat resilient and permit the pulverized or granulated material to be fed into the scoops through the notches 46^a, in addition to the open ends thereof, as the disc 40 is rotated in the direction of the arrow C.

One side of the reinforcing flange 41 of the disc 40 is formed with a depending knife member 47 for cutting the piece of paper normally positioned across the top of a powder box over the contained pulverized face powder as described in connection with the first form of the invention illustrated in Figs. 1 to 6.

It is believed that the operation of the form of the invention shown in Figs. 8 to 10 will be apparent from the operation described in connection with Figs. 1 to 6 and that a further explanation will be unnecessary.

While the arrangements of the scoops shown in Figs. 1, 7 and 8 are well adapted to the feeding of pulverized or granulated material, the arrangement of the scoops shown in Fig. 8 is also well adapted to scraping powder from solid cakes of such powder. This is so, as the spiral arrangement of the scoops 46 will be effective over the entire top face of the cake of powder and prevent the device from merely cutting ridges in the top face thereof.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a device for feeding pulverized material upward and having a flat disc for resting on the top surface of the material and a handle by which the disc can be rotated on the surface of the ma-

terial, means on the disc for feeding the pulverized material onto the top surface of the disc as it is rotated, comprising a depending formation at the center of the disc for throwing the pulverized material laterally from beneath the center of the disc as the disc is rotated, and depending scoops on the disc having open sides facing in the direction of rotation of the disc, said scoops increasing in size from said formation, outward so that the largest scoops are located adjacent the periphery of the disc to cover a large area adjacent the outer periphery of the surface of the pulverized material as the disc is rotated.

2. In a device for feeding pulverized material upward and having a flat disc for resting on the top surface of the material and a handle by which the disc can be rotated on the surface of the material, means on the disc for feeding the pulverized material onto the top surface of the disc as it is rotated, comprising a depending formation at the center of the disc for throwing the pulverized material laterally from beneath the center of the disc as the disc is rotated, and depending scoops on the disc having open sides facing in the direction of rotation of the disc, said scoops increasing in size from said formation, outward so that the largest scoops are located adjacent the periphery of the disc to cover a larger area adjacent the outer periphery of the surface of the pulverized material as the disc is rotated, said formation comprising a downwardly pressed four-pointed star.

3. In a device for feeding pulverized material upward and having a flat disc for resting on the top surface of the material and a handle by which the disc can be rotated on the surface of the material, means on the disc for feeding the pulverized material onto the top surface of the disc as it is rotated, comprising a depending formation at the center of the disc for throwing the pulverized material laterally from beneath the center of the disc as the disc is rotated, and depending scoops on the disc having open sides, said scoops increasing in size from said formation, outward so that the largest scoops are located adjacent the periphery of the disc to cover a larger area adjacent the outer periphery of the surface of the pulverized material as the disc is rotated, said scoops having their open sides positioned at a slight angle to the direction of rotation of the disc so that the material of said scoops defining the open sides thereof will have a cutting action on the pulverized material.

4. In a device for feeding pulverized material upward and having a flat disc for resting on the top surface of the material and a handle by which the disc can be rotated on the surface of the material, means on the disc for feeding the pulverized material onto the top surface of the disc as it is rotated, comprising a depending formation at the center of the disc for throwing the pulverized material laterally from beneath the center of the disc as the disc is rotated, and depending scoops on the disc having open sides facing in the direction of rotation of the disc, said scoops increasing in size from said formation, outward so that the largest scoops are located adjacent the periphery of the disc to cover a larger area adjacent the outer periphery of the surface of the pulverized material as the disc is rotated, each of said scoops having side walls formed with notches rendering the side walls flexible.

5. In a device for feeding pulverized material upward and having a flat disc for resting on the top surface of the material and a handle by which

the disc can be rotated on the surface of the material, means on the disc for feeding the pulverized material onto the top surface of the disc as it is rotated, comprising a depending formation at the center of the disc for throwing the pulverized material laterally from beneath the center of the disc as the disc is rotated, and depending scoops on the disc having open sides facing in the direction of rotation of the disc, said scoops increasing in size from said formation, outward so that the largest scoops are located adjacent the periphery of the disc to cover a larger area adjacent the outer periphery of the surface of the pulverized material as the disc is rotated, each of said scoops having side walls formed with notches rendering the side walls flexible, said notches being extended into the side walls from the open sides of said scoops for increasing the intake capacity of said scoops.
